UNITED STATES PATENT OFFICE.

HARRY DE FOREST MADDEN, OF NEWARK, AND JOHN JOSEPH HIGGINS, OF EAST ORANGE, NEW JERSEY, ASSIGNEES TO WESTINGHOUSE LAMP COMPANY, A CORPORATION OF PENNSYLVANIA.

AUTOMATIC CUT-TUBE-SORTING MACHINE.

Application filed May 9, 1921. Serial No. 468,125.

This invention relates to a machine for gauging and calibrating the outside diameter and wall thickness of tubular articles.

An object of the invention is to provide a machine which will rapidly and automatically gauge tubular articles, pass the gauged articles to an instrument for calibration, and then separate articles of given dimensions into groups.

10 Although the machine, as contemplated by the present invention, is adapted for gauging and assorting a variety of species of tubular articles, it is illustrated in the appended drawings and described herein as 15 being used for gauging and assorting relatively short lengths of such glass tubes as are used in connection with the manufacture of incandescent-electric-lamp parts.

In the manufacture of lamp parts, as, for 20 instance, the lamp stems which support the filaments, a substantial uniformity of dimensions is desirable in order that the parts, when assembled in a machine, may be automatically aligned for the production of a 25 complete stem of the desired accuracy.

When manufacturing the said lamp parts, it has been found preferable to use commercial glass tubing for the reason that such tubing is comparatively low in cost and 30 may be quickly and conveniently obtained. However, commercial tubing is usually manufactured in sections of several feet in length and inherently possess dimensional variations with respect to the inner and 35 outer diameters. It is, therefore, obvious that such tubing, when cut in short pieces for making lamp parts, results in a quantity of tubes having a variation between their respective dimensions; and the present 40 embodiment of the invention is particularly adapted to gauge and assort such short pieces of tubing, thereby making it possible to maintain the adjustment of certain lamp-part-producing machinery for receiving a 45 given size of tube. By thus providing a source of supply of tubes of given dimensions, the invention indirectly contributes to promote the efficiency of certain lamp-manufacturing machinery.

50 My invention will best be understood in connection with the accompanying drawings which are illustrative of one embodiment of the invention and in which:—

Fig. 1 is a side elevational view of a

tube-gauging machine, partly in section, and 55 with some of the calibrating mechanism removed;

Fig. 2 is an end elevational view of the upper part of the machine;

Fig. 3 is a diagrammatic plan view of 60 the mechanism which drives the operative parts of the machine, the gauging members being shown in dotted lines;

Fig. 4 is a fragmentary elevational view, partly in section, of a pair of calipers and 65 a support or carrier therefor and including a portion of the platform for carrying tube-receiving pins;

Fig. 5 is a fragmentary plan view of the calibrating device with one of the calipers 70 removed;

Fig. 6 is a side elevational view of a caliper, with a portion of the carrier shown in section;

Fig. 7 shows a caliper about to be moved 75 into an upper position;

Fig. 8 is a fragmentary elevation of one of the tube hoppers and chutes leading to one of the tube-receiving pins;

Fig. 9 is a plan view taken on line IX—IX 80 of Fig. 8;

Fig. 10 is an elevational view of a portion of the chute and stop mechanism shown in Fig. 8; and

Fig. 11 is a transverse cross-section taken 85 on line X—X in Fig. 10.

A preferred form of mechanism for practicing my invention comprises means for guiding tubes to a tube-gauging element, which is provided with one or more apertures through which the tubes pass to be gauged for their outside diameters. The gauged tubes are then collected into groups of like outside diameters, and the tubes of each group are transported to a conveyor which guides them into given positions adjacent to a calibrating element which is actuated to caliper the wall thickness. Following this operation, other means operate to cause the tubes of given wall thickness 95 to be collected into other separate groups. Thus, tubes of like outside diameters and like wall thickness or inside diameters are collected in respective compartments.

It will be apparent that the machine contemplated by this invention combines, in a convenient and simple structure, elements by which tubes of unlike dimensions may be

rapidly and easily assorted into groups of given dimensions, without the exercise of any particular skill and with but a small amount of attention on the part of the operator.

Referring now to the drawings and more particularly to Fig. 1, the members which constitute the gauging means may be mounted upon any suitable supporting structure which, as shown, preferably consists of a plate 2 secured to legs 3 and includes standards 4 and 5 for carrying a cross-member 6.

The mechanism for supporting the gauging means in an inclined position on the standard 4 preferably comprises bearings 7 and 8 in which are pivoted rods 12 which, in turn, adjustably support the gauging means. The upper ends of the rods are threaded and extend through lugs 13 of a crosshead 14; and the standard 5 has pivoted thereto a crosshead 15. The crossheads are each provided with laterally disposed projections 17 and 18, the projections 17 serving as bearings for a roller 23, which, 25 is one of a pair of rollers 23 and 24 mounted on suitable shafts to constitute, in the present embodiment of the invention, the gauging members. The roller 24 is supported in adjustable bearings 25 which are 30 mounted movably on rods 26 secured in the projections 17 and 18 of the cross-heads 14 and 15.

The bearings 25, being movable upon the rods 26, permit an adjustment of the distance between the gauging members or rollers 23 and 24. A suitably threaded portion is provided upon the rods 26, and the bearings 25 may thus be maintained in any given position by means of nuts screwed tightly 40 against the sides thereof.

For the purpose of conveying the tubes lengthwise of the gauging apertures, the rollers 23 and 24 are rotated; the roller 24 being connected to a supplemental drive shaft 27 by means of a universal coupling 30. The shaft 27 is supported in an extended bearing 31 fastened to the standard 5 and is rotated by means of a pulley 32 secured thereto and connected by a belt 33 to a pulley 34 which is secured to a horizontal shaft 35. This shaft is preferably driven by means of its connection to a main drive shaft 36 (see, Fig. 3), which, in turn, may derive motion from any suitable source of power as, for instance, by a belt connection between a pulley 37 secured thereto and a pulley fastened to the shaft of a motor (not shown). The connection between the shafts 35 and 36 consists in the engagement of an endless chain 38 with chain sheaves 40 and 41 secured to shafts 35 and 36 respectively. The said shafts are preferably journaled in suitable floor stand shaft-bearings 42 and 43 secured to a shelf 44 which is fastened to 65 the legs 3.

An opposite and simultaneous rotation of the shafts and, consequently, the rollers 23 and 24 may be produced by means of two meshing spur gears 45 and 46 which are secured to the respective shafts. It is obvious that, if desirable, one of the rollers may be made to serve as a stationary member, in which case the gears 45 and 46 may be omitted.

The gauging members or rollers 23 and 24 may be of any suitable design to perform the function of a gauging element, and, in the present embodiment of the invention, each of the rollers is turned down or otherwise constructed to provide a series of annular steps 47, 48 and 49, and each roller constitutes a member consisting of a plurality of integral cylinders of graduated diameters.

As shown in the drawing, the cylinders are preferably disposed with their respective larger ends adjacent and their axial lines parallel and are positioned in a common inclined plane. This disposition of the rollers provides an aperture therebetween of varying widths throughout the length of the rollers. Each pair of opposed cylinders of equal diameter provides what will be hereinafter termed a gauging aperture, and the number of such apertures will be governed by the steps in the rollers. It is therefore obvious that the number of such steps may be increased or decreased according to the desired range of tubes of given diameters to be assorted. The present embodiment of the invention shows four such apertures, 51, 52, 53, and 54. The rollers, together with the apertures therebetween, will hereinafter be termed a gauging element.

The angle of the plane in which the gauging element is supported may be varied by the adjustable screw connection between the lugs 13 and the threaded ends of the rods 12. Means, in the form of locknuts, being provided to secure the lugs and rods in a given position to maintain the crossheads 14 and 15 and, consequently, the rollers 23 and 24 in a given plane.

The tubes to be gauged and separated are fed to the rollers and are guided first to the smaller aperture 51, and any tubes, the diameters of which may be smaller than the width of the said aperture 51, drop through and are guided to a suitable compartment. This initial aperture therefore serves as a means of elimination for all tubes having diameters below the minimum size of tubes to be gauged. Other tubes move down the inclined rollers until they reach an aperture of the proper dimension through which they pass and drop into suitably disposed hoppers 55, 56 and 57 positioned beneath the apertures 52, 53 and 54, respectively. All tubes having diameters above a given range and too large to pass through any of the apertures will continue to move downwardly

and finally fall from the ends of the rollers into a suitably positioned receiver 58.

It will be understood that each of the hoppers 55, 56 and 57, disposed below the effective gauging apertures serves to accumulate tubes gauged by the respective apertures. Tubes, having thus been separated into groups of given outside diameters, are reassorted for inside diameters by means of a device which calibrates the walls of the tubes, and the tubes of like diameters are, by this means, separated into sub-groups of like wall thicknesses and, consequently, of like inside diameters.

To accomplish this, second separation, a calibrating device is preferably employed in a position adjacent to each of the hoppers 55, 56 and 57. Each device comprises a reciprocating spindle 59 to which is fastened a support or carrier 61 composed of a segmental plate upon which a plurality of calipers are movably mounted. The selected design of caliper and its operation will be hereinafter more fully described.

Tubes to be calibrated are moved, preferably by gravity, to rotary platforms 62 where they are positioned to receive the calipers. The platforms are adapted to be revolved about spindles 59, and are provided with hubs 63 which bear upon the upper ends of cylindrical guides 64 rigidly secured to the plate 2. Within the guides and rotatable about the shaft 59 are disposed hollow shafts 65 which transmit rotational movement to the platforms. The platforms 62 are secured to shafts 65 by means of set screws 66 and these shafts are capable of being rotated about the spindles 59. Preferably, two of the spindles 59 are reciprocated by means of their connection with the shaft 35 and the remaining spindle through its connection to the main driving shaft 36.

The connections to the driving shafts preferably consist of links 68, which are pivotally attached to the spindles 59 and to cranks 69 fastened to the shafts 35 and 36. Suitable mechanism for rotating the platforms 62 includes notched circular plates 71 having hubs 72 which are secured to shafts 65 by means of set screws 73. Plates 71 are adapted, in co-operation with other mechanism, to effect the intermittent rotation of the platforms 62. This movement is preferably obtained through suitably disposed bifurcated members 74 (see Fig. 3) which are provided with pins 75 and 76 positioned to drive the plates 71 and, consequently, the platforms 62. Such mechanisms provide for two consecutive steps of the rotary movement of each platform with the complete revolution of each member 74.

The driving member 74 is provided with a hub 78 pinned to a vertical shaft 79 which extends to a point above the plate 2 and is secured against vertical movement by means

of a collar 80 fastened to the upper end thereof. The notched plates 71 and the platforms 62 secured thereto are driven in unison by means of an endless chain 81 which engages with chain sheaves or sprockets 82 secured to the shafts 79, and with a drive sheave 84 fastened to a vertical shaft 85 journaled in a sleeve 86 secured to the plate 2. The shaft 85 is maintained in operative position by the provision of a collar 87 fastened to its upper end. The lower end 88 of the shaft is provided with a miter gear 89 disposed in mesh with a similar gear 90 fixed to one end of a horizontal shaft 91 carried in a bearing 92. Secured to the opposite end of the shaft 91 is a chain sheave 93 connected by means of an endless chain 96 to another sheave 97 attached to the driven shaft 35.

The rotation of the driving shaft 36 rotates the shaft 35 which, in turn, transmits a reciprocative motion to the spindles 59 and segments 61 by means of the cranks 69.

Disposed at intervals adjacent the periphery of the platforms 62 and positioned in circular alignment, are alternately arranged vertical pins 98 and apertures 99 (see Fig. 5). The pins 98 are provided to receive tubes from the hoppers 55, 56 and 57 and to support them in vertical positions to be calibrated. The apertures 99 are provided to permit the passage of tubes through the platform after calibration. Each tube-receiving pin may be equipped with a spring member 100 secured to an adjacent collar 102 disposed above the aperture 99 and so positioned as to have its end adjacent to a pin 98. Thus, as a tube is positioned on a pin, the wall thereof passes between the spring member 100 and the pin and is maintained in contact with a given side of a pin. By this means, a tube is automatically adjusted to a given position on the platform to be caliperized. The springs 100 may, if desirable, be omitted as it is evident that the ends of the caliper arms may be chamfered, as shown, and, therefore, be readily guided over the wall of a tube in the event that a positioned tube does not register exactly beneath the opening between the ends of the caliper.

Tubes, which have been caliperized and dropped through the apertures 99 by the operation of mechanisms hereinafter described, are guided to bins by means of the collars or guides 102 and chutes 101.

The calipers for gauging the wall thicknesses of the tubes preferably comprise arms 103 and 104 which are carried by the supports 61 positioned above platforms 62. The arm 103 of each caliper consists essentially of a rod vertically slidable in a suitable hub integral with the segment 61. The arm 104 is constructed to be the relatively movable member of the calipers and is preferably pivoted in a bearing 105 in-

tegral with, and projecting at right angles to, the rod 103. The rockable arm 104 is provided with a set screw 106 for adjusting the size of opening between caliper 5 points 107 and 108. When the arms have been set to a given normal opening, the opening is maintained through the agency of a flat spring 110 which is fastened to the rod 103 to exert a slight pressure upon the arm 104, causing it to keep the end 111 of the set screw 106 in contact with the rod 103.

By means of such adjustable calipers, a 10 calibrating element may be provided with a 15 plurality of predetermined graduated openings to accommodate a given range of thicknesses of tube walls.

Each caliper, as heretofore mentioned, is 20 movable vertically in its hub, and it is desirable to provide a suitable means for maintaining each caliper in a normal upper position for a certain period of time. This is 25 accomplished by the provision of a suitable latch comprising a bent-arm lever 112 which is fulcrumed on a pin 113 in a bearing 114 which, in turn, is preferably integral with the support 61. The lever is constructed with an offset portion 115 which provides a stop adapted to be normally retained, by 30 means of a spring 116, in the path of a pin 117 fixed to the rod or caliper arm 103. The calipers are thus normally held in their upper positions and are moved into contact with the tubes by the actuation of the mechanism which reciprocates the segment or support 61.

When the segment is moved downwardly 40 and the caliper arms slip over a wall of a tube the thickness of which approximates the distance between the points 107 and 108, the tube is frictionally retained between the said points, and, upon the upward movement of the segment, the tube is lifted from pin 98 upon which it had previously been 45 positioned.

The co-operating mechanisms are timed 50 to rotate the platform 62, as the calipers move upwardly, to bring the apertures 99 beneath the suspended tubes at which time mechanisms are actuated for spreading the calipers to release the tubes and permit them 55 to drop into suitable containers. A selected releasing means consists of a projection or stop 118 formed integral with the segment 61 so disposed in relation to the arm 104 60 that, as the latch or lever 112 releases the caliper and it drops downwardly, the arm 104 engages the stop 118, thereby effecting an inward movement of the arm and causing the separation of the points 107 and 108 to release a tube.

In returning the calipers to normal or closed position, they are released from engagement with projection 115 of the 65 lever 112 by a suitable means which, in the

present construction, comprises a rigid bracket 119 secured to the framework of the machine and positioned above the calipers. Disposed in the said bracket and located directly above each of the rods 103, is a set 70 screw 120 which affords an adjustable stop for the said rod, and, positioned above each of upper arms 121 of the lever 112, are adjustable stop pins 122.

When one of the calipers is moved upwardly with the segment 61 the pins 122 engage the arm 121 of the lever 112 to cause the projections 115 to move from the path of the pins 117 to release the caliper arms and permit them to drop, with a consequent 80 opening of the arms thereof, as above explained. The calipers may be permitted to drop by reason of their potential energy; the set screw 120, however, provides for a 85 more positive movement of the calipers in the event that their movement may be retarded by friction. The rod 122 is so arranged as to actuate the latch just previous to the contact between the set screw 120 and the upper end of the rod 103.

The calipers having moved to their lower positions, it becomes necessary to return them to their upper or calibrating positions to be latched. This is accomplished by the downward movement of the segment 61 the actuation of which is timed to move the end 107 of the rod 103 into contact with a pin 98 which arrests the movement of the said rod and permits a slight downward travel of the lever 112 until the face of the projection 115 has moved to permit the said projection to pass below the pin 117 and thus lock the caliper against independent downward movement. The face of the projection 115 is constructed of sufficient length to permit a constant tensional contact with the pin 117 when the caliper is in its lowest position with relation to the segment 61.

Referring to Fig. 7, the projection 115 is shown as it is about to pass beneath the pin 117, and Fig. 6 shows the calipers in their lowest position with relation to the segment 61 and with the arm 104 in contact with the stop 118, in which position the points 107 and 108 are opened to release a tube. This figure also shows a tube about to pass through one of the apertures 99 from which it is guided by means of chute 101 to a given compartment or hopper.

The tubes having been separated and accumulated in receptacles in accordance with their respective outside diameters, may be fed individually to the tube-receiving pins 98 for calibration by any suitable means, one such mechanism being shown in the accompanying drawings as comprising an oscillating lifting plate 123 pivoted on a pin 124 carried in a bearing 125 fixed to the cross member 6. Preferably this lifting plate is moved in a vertical plane and its upper edge 130

is provided with a recess 126 of V shape into which the tubes move by reason of an inclined hopper bottom; the base of the incline being flush with the edge of the plate 123 when in its lower position, as shown in dotted lines in Fig. 8.

Tubes are ejected from any one of the hoppers 55 etc., by the upward movement of the lifting plate 123 which lifts one or 10 more tubes. The angle to which the plate is raised is sufficient to cause the tubes to slide downwardly and into one of the suitably positioned flared chutes 127 which terminate in a tubular guide 128.

15 The plate 123 actuates to eject a tube with each upward movement of the segment 61 by means of its connection therewith. The connection comprises a pin 129 secured to a hub 130 of the segment 61, and the end of 20 this pin is disposed in slidable engagement with a strap or yoke 131 fastened to the underside 132 of the plate 123, by means of tap bolts 133 and 134. The said plate is therefore moved with each movement of the 25 segment 61 and tubes are caused to enter the chute 127 successively.

The open lower end of the guide 128 is disposed directly above the path of travel of the pins 98 and the apertures 99, in the 30 platform 62. The platform operates by means of the driving member 74, to position a pin 98 in vertical alignment with the chute 128 during each of its stationary periods, to receive a tube.

35 In order to automatically control the disposition of tubes upon the receiving pins 98, a means for feeding the tubes singly to the pins may be provided by any suitable alternate stop-and-release mechanism. A selected mechanism is illustrated in the drawing as comprising a rocking lever 137 adapted to effect an intermittent stop and release of the tubes moving down the chute 128. This rocking lever 137 is preferably ful- 40 crumed on a projection 138 formed integral with a tubular member 139 carried upon an arm 140 secured to a post 141 which, in turn, is fastened to the plate 2. The upper end of the lever 137 is provided with a V 45 notch 142 and is adapted to intermittently press against, and secure a tube in contact with, the side of the guide 128, as shown in Fig. 11. An aperture 145 is provided in the chute 128 for the entrance of the notched 50 end of the lever 137. The lower end of the lever is bent to provide a right-angle projection 146 which is normally disposed in the path of the tubes.

The rocking lever is actuated with each 55 movement of the platform by means of the engagement of a rod 147 with the collars 102 which move with the platform 62. The said rod is fastened to a vertical shaft 148 journaled in a projection 150 of a collar 151 and the arm 140. A movement of the plat-

form 62 moves one of the collars 102 in contact with the rod 147, one end of which lies in the path of movement of the collars to effect the oscillation of the shaft 148 which, in turn, causes the actuation of the lever 137 70 through the movement of a finger 155 secured adjacent to the upper end of the shaft 148, and which extends through a slot 156 disposed in the lower arm of the lever 137. A helical spring 158 connected to the said 75 finger and to a pin 157, secured to the arm 140, acts to maintain the said lever in a normal position with the end 146 in the path of the tubes in the chute 128. Thus, the end of the lever 137 normally prevents the downward movement of the tubes, but, as the platform 62 rotates and one of the collars 102 bears against the end of the rod 147, the lever 137 is rocked and the notched end thereof is pressed against a tube to temporarily retain it in position, at the same time the projection 146 is removed from the path of the lowest tube, permitting it to drop upon one of the pins 98.

With each complete revolution of the bifurcated member 74, the platform 62 is moved two steps, and the cooperating mechanism is so timed that, during the initial step, the caliper carrier is moving upwardly and the platform is positioned with tube-receiving pins 98 beneath the chutes. The tubes drop onto the pins and, as they are being positioned, the apertures 99 register beneath the calipers. As the carrier moves upwardly, the calipers are first actuated to release any tubes which may be held between their measuring points, as above explained. The next progressive movement of the platform brings the pins 98, and, consequently, the tubes positioned thereon, beneath the calipers and then the carrier moves downwardly, causing the calipers to calibrate the walls of the tubes and lift one or more tubes from the pins.

Each calibrating device may have associated therewith any number of calipers each of which may be adjusted to provide a differently dimensioned calibrating opening; thus, a series of graduated openings are obtained. It has been found, in practice, when 110 gauging glass tubes for use in making certain lamp parts, that a series of five calipers is sufficient to provide a range of calibrating openings to accommodate the variation between the wall thicknesses of such tubes. 115

It will thus be readily understood that, if the ends 107 and 108 of the arms of one of the calipers are applied to a positioned tube and the tube is not of the proper thickness to be gripped by the said ends it remains upon the pin, and mechanism operates to move the tube beneath another pair of calipers the ends of which are moved in contact with the walls of the tube. This 120 operation is repeated until the tube is finally 130

picked up by a pair of calipers and deposited in a given compartment by the actuation of mechanism which opens the arms to release a suspended tube.

5 The above described machine, therefore, provides a means for gauging and sorting or grouping tubes of like outside diameters and again assorting the gauged tubes into subgroups of given wall thicknesses and, 10 consequently, like inside diameters.

While we have illustrated a preferred embodiment of our invention it is to be understood that many structural changes may be effected therein. As, for instance, where

15 desirable, the rollers may be utilized to separate tubes into groups of a given outside diameter without the employment of the calibrating devices. Again, the calibrating devices may be employed to separate tubes

20 into groups of given wall thicknesses; or the mechanism may be arranged in such manner as to provide for the separation of tubes of given inside diameters by means of the said calipers after which they may

25 be again separated for outside diameters by means of the rollers which constitute the gauging element. It is to be understood that such and other modifications are to be considered within the scope of the appended

30 claims.

What is claimed is:

35 1. In a machine for gauging the outside diameter and the wall thickness of tubes, the combination of an element for gauging the diameter of tubes, means for feeding gauged tubes from said gauging element, means for supporting the gauged tubes of a given diameter in groups, a caliper element in operative relation to each group, means for moving said caliper elements to engage and caliper the wall thickness of said supported tubes, means for moving said caliper elements to remove the tubes from said supporting means and means for releasing tubes of given diameters and wall thickness for deposit in a common receptacle.

40 2. In a tube gauging machine, the combination of a rotary cylindrical tube diameter gauging element adapted to gauge and discharge gauged tubes of different diameters in groups at a plurality of stages along its length, a plurality of caliper elements for engaging and caliper the walls of the respective groups of gauged tubes, a carrier for each group of said tubes, means for actuating said carrier to position said caliper elements in operative relation to said gauging element, means for supporting the respective groups of tubes gauged by said gauging element, means for actuating said caliper elements to engage and caliper the walls of tubes of different thicknesses and means for actuating said caliper elements to release said tubes for deposit in

separate groups in accordance with their diameters and wall thicknesses.

3. In a tube gauging machine, the combination of a gauging element comprising a plurality of pairs of cylinders, a plurality of caliper elements, means for disposing caliper elements in operative relation to each of said pairs of cylinders, means for delivering tubes gauged by said cylinders to the caliper elements, means for caliper the walls of the delivered tubes and means for actuating said caliper elements to deposit tubes of different wall thicknesses in different groups.

4. A tube assorting machine comprising a plurality of pairs of cylindrical gauging members, means for applying tubes to said members for a gauging operation to separate tubes of different diameters into groups, a calibrating element disposed in operative relation with each group of tubes, means for operating a calibrating element to caliper the walls of tubes of each group and means for actuating said calibrating element to deposit tubes of different wall thicknesses and diameters in different groups.

5. A tube assorting machine comprising a number of cylindrical, tube diameter gauging members positioned to provide a varying spaced relation between the diameters thereof, calibrating elements disposed at intervals along the length of said gauging members, a plurality of tube feeding devices disposed in spaced relation along the length of said gauging members, each device being arranged to receive tubes of a given diameter, means for actuating said devices to feed tubes individually, supporting means for receiving and supporting tubes fed from said devices, means for operating said caliper elements to engage and caliper said supported tubes, means for moving said caliper elements to gauge and remove tubes from said supports and means for actuating said caliper elements to release calibrated tubes of different wall thicknesses for deposit into different groups.

6. A tube assorting machine comprising a tube diameter gauging member having a plurality of gauging apertures, a plurality of caliper elements mounted on a carrier in operative relation to each of the gauging apertures, supporting means for gauged tubes, tube feeding devices for transferring gauged tubes from the gauging apertures to said supporting means, means for actuating said carriers to move caliper elements successively in operative relation with supported tubes, means for moving said caliper elements to engage and lift a tube having a given wall thickness and means for actuating said caliper elements to release tubes of different wall thicknesses for deposit in different groups.

7. In a tube assorting machine, the combi-

elements consisting of a plurality of calipers, the arms of the several calipers being adjusted to provide a plurality of graduated openings, means for guiding objects through 5 said gauging apertures, means for conveying objects passed through the respective apertures to a given calibrating element, means for successively applying a given caliper element to gauged tubes and means for depositing tubes having a wall thickness substantially corresponding to the opening of given calipers into separate groups.

16. A machine for assorting a plurality of tubular bodies of varying dimensions comprising a device including two rollers adapted to provide a plurality of gauging apertures, means associated with said device for applying tubular bodies to said apertures, means for rotating the rollers in opposite directions to oppose the action of the potential energy of the bodies during their passage between the rollers, means adjacent each of said gauging apertures for receiving gauged tubes and for supporting the same vertically 20 and caliper elements for caliperizing the wall thickness of the positioned tubes.

17. In a machine, the combination of a gauging element, a pair of stepped rollers positioned to provide a plurality of gauging 30 apertures there between, means for feeding tubular bodies to said apertures, means for rotating the rollers in opposite directions to produce a slight opposition to the potential energy of said bodies during their passage through said apertures for a gauging operation, means for guiding bodies gauged by the several apertures into different groups, means for interiorly engaging said bodies to maintain them in given spaced relation and means for measuring the wall thickness of said positioned bodies.

18. In a tube gauging machine, a calibrating device comprising a carrier, a caliper having gauging points mounted on said carrier, means for supporting a tubular object to be caliperized, means for tensionally maintaining said gauging points in a given spaced relation, means for moving said caliper to cause the gauging points to 45 make contact with the opposite sides of the wall of said tubular object to frictionally engage the same and means for actuating said caliper to lift the tubular body from said support.

55. 19. In a tube gauging machine a caliper device comprising a carrier, a caliper having movable gauging points mounted upon said carrier, means for supporting a plurality of tubular objects, means for tensionally maintaining said caliper points in a given spaced relation, means for actuating said caliper to engage the points thereof with opposite sides of a wall of a tubular object and means for actuating the caliper to lift the object 60 when the wall thereof is of sufficient thick-

ness to frictionally engage with said caliper points.

20. In a machine, a calibrating device comprising a carrier, a plurality of calipers mounted upon said carrier, means for supporting a plurality of tubular objects in position to be calibrated, means for moving said calipers to successively calibrate the walls of said objects and means for delivering objects of like wall thickness into separate groups.

21. In a tube gauging machine, a caliperizing device comprising a carrier, a plurality of calipers mounted on said carrier having caliperizing points, means for tensionally holding each pair of said points in a given spaced relation, means for adjusting said points, means for supporting objects in position to be caliperized, means for moving a pair of caliper points successively in contact with the walls of said objects and means for actuating one of said calipers to lift an object having a wall of sufficient thickness to be frictionally engaged by said caliper points.

22. In a machine, a calibrating device comprising a carrier, a plurality of calipers for gauging the wall thicknesses of tubular objects mounted upon said carrier, means for supporting objects in position to be calibrated, means for adjusting the arms of said calipers to provide a series of graduated calibrating openings, means for moving said calipers successively in contact with the wall of said objects and means for conveying calibrated objects into groups having walls of like thicknesses.

23. A machine having a calibrating device comprising a carrier having a plurality of calipers mounted thereon, each of said calipers having a pair of calibrating points, means for maintaining said points a given distance apart, means for moving said calipers to position said objects successively between said caliper points, means for actuating said calipers to raise an object having sufficient dimensions to be frictionally engaged by said caliper points and means for releasing said object.

24. In a machine, a calibrating device comprising a carrier having a plurality of calipers mounted thereon, means for supporting tubular objects in position to be caliperized, means whereby said calipers are caused to lift objects of given wall thickness, means for changing the relative position of said support and calipers, means for actuating calipers to release objects held thereby and guides for leading released tubes to containers.

25. In a machine, a calibrating device comprising a carrier having a plurality of calipers mounted thereon, a support for tubular articles to be calibrated, means for moving the points of each pair of caliper

- nation of the gauging element having a plurality of gauging apertures, a calibrating element, means for actuating said gauging element to affect the passage of gauged tubes 5 through said apertures, means for arranging gauged tubes in position to be calibrated and means for actuating said calibrating element to calibrate the walls of said tubes of given diameters and to deposit tubes of like wall 10 thickness and diameters in common groups.
8. In a tube-gauging and sorting machine, the combination of two oppositely rotatable stepped cylindrical members positioned to provide a plurality of gauging apertures 15 therebetween, a calibrating member disposed adjacent to each of the respective apertures, means for feeding tubes to be gauged by said apertures, means for positioning gauged tubes for calibration by said calibrating 20 member, means for actuating the said member to bring the arms thereof into contact with the walls of said tubes and means for actuating said caliper member to deposit tubes of like dimensions into separate groups.
9. In a tube assorting machine the combination of a stationary member and a rotary member positioned to provide a gauging aperture therebetween, a calibrating element disposed adjacent to said gauging aperture, 25 means for arranging gauged tubes of like diameters in position to be calibrated, means for actuating said calibrating element to engage the walls of said tubes and means for moving said element to deposit tubes of like wall 30 thickness and diameters in common groups.
10. In a tube assorting machine the combination of a tube diameter gauging element and a wall thickness calibrating element, the said gauging element constituting two rollers 35 positioned to provide a plurality of gauging apertures therebetween, said calibrating element comprising a pair of adjustable arms, means for directing tubes to said gauging element for passage through said gauging 40 apertures, means for arranging gauged tubes of like diameters in position for engagement by said calibrating element and means for actuating said calibrating element to caliper and deposit tubes having like diameters but 45 of different wall thickness in different groups.
11. A machine for assembling tubular bodies into groups of given outside diameters and in re-assembling the said groups into other groups of like inside diameters, said 50 machine comprising a pair of rollers disposed to provide a gauging aperture therebetween, a platform having a plurality of tube-receiving pins, means disposed lengthwise of said aperture to guide tubes passing 55 therethrough to given pins, a pair of calipers disposed above each of said pins, means for successively moving said calipers in contact with each gauged tube and means for actuating the calipers to release a tube when 60 engaged thereby.
12. A machine for sorting tubular bodies comprising a pair of stepped rollers having their axial lines parallel and adapted to provide a plurality of gauging apertures therebetween, means for adjusting the relative 65 positions of said rollers to vary the spacing of the gauging apertures, a rotatable platform disposed adjacent each of said apertures, pins arranged at intervals about said platform, a caliper disposed above each of said pins, guide members associated with said rollers and said pins for directing tubes passing through said apertures on to said pins, means for successively moving the arms of the several calipers in contact with the walls of the tubes, means for causing said arms to lift a tube from a pin and means for actuating said arms to release a suspended tube.
13. A machine for assorting tubular bodies according to diameter and wall thickness comprising a pair of rollers positioned adjacent to each other with their axial lines parallel and adapted to provide a gauging aperture, a rotary platform disposed adjacent to said rollers, said platform having vertical tube-receiving pins positioned thereon, a pair of calipers disposed above each of said pins, means for adjusting each caliper with a relatively different arm position, 95 means for guiding tubes which pass through the gauging aperture to said pins, means for moving the calipers successively in contact with the walls of the positioned tubes to cause a given tube to be gripped by a given 100 caliper, means for moving a caliper and tube held thereby and means for actuating the calipers to release a gripped tube.
14. A machine for assorting tubular bodies according to diameter and wall thickness 105 comprising a pair of rollers positioned adjacent to each other with their axial lines parallel to provide a gauging aperture, a rotary platform disposed adjacent to said rollers having vertical tube-receiving pins positioned thereon, a pair of calipers disposed above each of said pins, means for adjusting each caliper with relatively different positions of the calibrating points, means for guiding tubes which pass through the gauging 110 aperture to said pins, means for moving the calipers successively in contact with the walls of the tubes to cause a given tube to be gripped between the points of a given 115 caliper, means for moving a caliper and tube held thereby, means for actuating the calipers to release a gripped tube and means for guiding tubes released by a given caliper to a given compartment.
15. A machine for assorting tubular objects according to diameter and wall thickness comprising a gauging element and one or more calibrating elements, said gauging element having a plurality of graduated 120 gauging apertures, each of said calibrating 125

- arms successively in contact with said articles, means for causing said points to grip tubes of a given thickness, means for actuating said carrier to lift tubes gripped by said calipers, means for changing the relative positions of said carrier, said calipers and means for actuating said calipers to release tubes secured thereby and means for guiding released tubes of like thicknesses into groups.
26. In a machine, a calibrating device comprising a carrier having a plurality of calipers mounted thereon, a support for tubular articles to be calibrated, means for moving the points of each pair of caliper arms successively in contact with said articles, means for causing said points to grip tubes of a given thickness, means for actuating said carrier to lift tubes gripped by said calipers, means for changing the relative positions of said carrier and said calipers, means for actuating an arm of the calipers to release the tubes and means for guiding released tubes to respective groups.
27. In a machine, a calibrating device comprising a carrier having a plurality of calipers mounted thereon, said calipers being adapted for vertical movement and positioned with their calibrating points depending, a support for tubes to be calipered, said support having a plurality of alternately disposed apertures and tube receiving pins, said support being positioned beneath said calipers, means for actuating said support to position the apertures and pins successively beneath said calipers, means for moving said support to engage said caliper points with the walls of said tubes, means for causing the caliper points to grip tubes, means for raising said calipers, means for moving the said support to bring said apertures beneath said calipers, means for releasing gripped tubes to permit them to pass through said apertures and means for guiding tubes from the respective apertures to containers.

In testimony whereof, we have hereunto subscribed our names this 7th day of May, 1921.

HARRY DE FOREST MADDEN.
JOHN JOSEPH HIGGINS.
